(57) CLAIM

The ornamental design for a display screen having an icon, as shown and described.

DESCRIPTION

The file of this patent contains at least one drawing executed in color. Copies of this patent with color drawing(s)/photograph(s) will be provided by the Office upon request and payment of the necessary fee.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a first embodiment of a display screen having an icon. The colors shown in the first embodiment of the graphic include orange (HEX #E77621/RGB 231/118/33), steel (HEX #3E4543/RGB 62/69/67), and chrome (HEX #CCCCCC/RGB 204/204/204).

FIG. 2 is a front view of a second embodiment of a display screen having an icon; and,

FIG. 3 is a front view of a third embodiment of a display screen having an icon.

The outermost broken line showing the display screen in all the figures and all the broken lines shown in FIG. 3 are included for the purposes of illustrating portions of the article that form no part of the claimed design.
